INTERNAL COMBUSTION ENGINE

Application filed January 23, 1930. Serial No. 422,758.

The invention relates to internal combustion engines, and more particularly to a system wherein two gas explosions are produced in a single piston stroke.

5 In ordinary operation of an internal combustion engine gasoline or oil is converted into gas which is compressed at one end of the piston stroke and while under such compression the gas is ignited by means of a
10 spark plug or other ignition means. The ignition of the gas creates heat from which is obtained power by the expansion of the gases under the influence of the heat. The incomplete burning of the gas or oil produces large
15 quantities of carbon monoxide gas, which is still combustible, and which is a very poisonous gas. The carbon monoxide is discharged from the exhaust pipe of the engine into the atmosphere, and is a menace to public health
20 as well as a waste of a valuable combustible gas.

The present invention aims to reduce the quantity of carbon monoxide delivered from the exhaust pipe, by producing substantially
25 complete combustion within the engine cylinders. This is accomplished according to the present invention by producing a second ignition of the gases within the cylinder and a second expansion of said gases on the same
30 stroke of the piston as the first ignition, and before the commencement of the scavenging stroke. To accomplish this it is necessary to provide means for supplying auxiliary air, and injecting it at the right time into the
35 engine cylinder, and at the same time producing a spark.

The invention will be more readily understood by reference to the accompanying drawing showing an illustrative embodiment of
40 the principles of the invention. In the drawing,

Fig. 1 is a view partly in section through an engine cylinder and partly in diagrammatic elevation showing the timer and system for supplying compressed air; and

Fig. 2 is an enlarged detail sectional view showing the fitting through which compressed air is supplied to the engine cylinder.

50 As shown, the reference numeral 10 denotes a water jacketed cylinder which may be of any

well known or standard construction. Within the cylinder is a piston 11 which is likewise of standard construction, and extending into the upper portion of the cylinder is a
55 spark plug 12. The numeral 13 denotes the expansion chamber located above the piston, and into which extends the spark plug 12. Communicating with the expansion chamber are intake and exhaust valves 14 and 15 leading respectively to the intake manifold and
60 to the exhaust manifold. The above features are or may be of any well known standard construction.

According to my invention, means are provided for supplying air under pressure to
65 the expansion chamber 13 at a time shortly after the beginning of the expansion stroke. As shown, a fitting 16 is screwed into the wall of the cylinder 10, such fitting being provided with a tapered nozzle or jet 17 which narrows to a small outlet communicating with a
70 passage 18 leading to the expansion chamber 13. The outlet opening of the jet 17 and the passage 18 may be very small, preferably about $\frac{1}{16}$ th of an inch in diameter. A flap
75 valve 19 is suitably mounted in rear of the fitting 16 in such a manner as to close when the pressure on the engine side exceeds that on the side of the pipe 29.

I have provided a means for supplying
80 compressed air to the fitting and controlling such supply from the dash board of the vehicle. As shown, the source of pressure is an air pump 20 which may be operated from the driving shaft of the vehicle or in any suitable manner. This pump communicates through pipe 21, non-return check valve 22 and pipe 23 with a pressure reservoir 24 designed to equalize the pressure supplied to the cylinder. Leading from this reservoir
85 is a pipe 25 in which is located a valve 26 manually controlled by means of a rod 27' operable from the dash board of the vehicle. From the valve 26 a pipe 27 leads to a drain box 28, preferably of large proportions, from
90 which pipe 29 leads to a fitting 30 within which is mounted the flap valve 19 previously referred to, from which pressure is supplied through fitting 16 and passage 18 to the
95 expansion chamber 13. The use of the man-
100

ually controlled valve 26 makes the second reservoir or drain box 28 desirable. This reservoir is designed to hold a substantial quantity of compressed air, and when the valve 26 is cut off, the auxiliary air from the drain box will flow for a short period into the cylinder. A certain amount of water will be found to accumulate in the system, and this will settle in the bottom of the drain box 28, which is the lowest part of the system. The tank is accordingly provided with suitable means, not shown, such as a drain cock, for periodically withdrawing the water which accumulates in the bottom of the tank.

15 It is necessary to provide means for producing a second spark or ignition at a suitable period after the first ignition. For this purpose I provide a suitable timing or ignition mechanism generally designated by the 20 reference numeral 31. The numeral 32 denotes any suitable source of electrical power and the wire 33 leads therefrom to the spark plug 12, a suitable transformer 38 and condenser 39 of conventional form, or other well-known spark producing devices being interposed between the source of power and the spark plug. The timer 31 is provided with a suitable contact point 34 which may be grounded as at 34'. The features of the 25 timer hereinabove described are or may be of standard construction. For accomplishing the dual ignition, however, I have provided a contact arm 35 having branches 36 and 37 designed to successively contact with the point 34 at short intervals.

30 The operation of the device will be readily understood from the above description. Beginning at the expansion stroke of the piston, ignition takes place on the contact of arm 36 with point 34, thus producing the usual explosion. When the piston has moved to the position shown in the drawing, the second contact arm 37 reaches the point 34, and at the same instant the passage 18 is uncovered, permitting compressed air to enter the expansion chamber 13. This produces a second explosion which materially reduces the proportion of carbon monoxide in the gases within the cylinder, and furthermore produces additional power by the burning or combustion of such carbon monoxide or other gases which may not have been thoroughly burned at the first ignition.

35 The auxiliary air admitted through the passage 18 also assists in the scavenging operation during the scavenging stroke. Obviously no back pressure can pass the valve 19 which immediately closes on the building up of excess pressure on the engine side of said valve. If it is desired to cut off the supply of compressed air and to operate the device in the ordinary manner, this may be readily accomplished by closing the valve 26 by means of the rod 27' operable from the dash.

The gases which are passed from the exhaust pipe when using my dual explosion system contain a much larger proportion of carbon dioxide as compared with the poisonous carbon monoxide than in ordinary practice, and thus contamination of the atmosphere is materially reduced.

70 The invention has been described in detail for the purpose of illustration, but it will be evident that the details are for the purpose of illustration, and are not to be construed by way of limitation of the scope of the invention.

75 If desired the timer arms 36 and 37 may be made relatively adjustable to control the period between ignitions.

80 What I claim is:

1. In combination with an internal combustion engine, means for producing a dual explosion during a single piston stroke, said means including a suitable ignition device, a timer having an additional arm for producing a spark at a suitable interval after the first explosion, and means for supplying compressed auxiliary air to the cylinder simultaneously with the second ignition, the means for supplying compressed air comprising a pump, a compressed air reservoir for receiving air from the pump, a check valve located between the pump and reservoir, a drain tank beyond the said reservoir, a manually operated valve in the passage between the drain tank and reservoir, a passage leading from the drain tank to the cylinder, a one-way flap valve in said passage to prevent return of pressure from the cylinder, a fitting having a jet nozzle therein, interposed between the flap valve and the cylinder, and a relatively reduced passage through the cylinder wall between said fitting and the interior of the cylinder.

90 100 105 110 115 120 125 130

2. In combination with an internal combustion engine, means for producing a dual explosion during a single piston stroke, including means for producing two ignitions at timed intervals, and means for supplying compressed auxiliary air to the cylinder during the second ignition, said means for admitting compressed air including a pump, a reservoir, a passage leading from the reservoir to the cylinder, a one-way valve in the passage to prevent return of pressure from the cylinder, a fitting having a jet nozzle therein, interposed between the valve and the cylinder, and a relatively reduced passage through the cylinder wall between said fitting and the interior of the cylinder.

135 140 145 150 155 160 165 170

3. In combination with an internal combustion engine, including a cylinder, a piston working therein, intake and exhaust valves, and an ignition device adapted to produce a dual ignition during a single piston stroke, means for supplying auxiliary air to the cylinder under pressure as soon as the inlet is uncovered by the piston, said

means including a pump, a reservoir for receiving air from the pump, a passage leading from the reservoir to the cylinder, a one-way valve in said passage to prevent return of pressure from the cylinder, a fitting having a jet nozzle therein, interposed between the flap valve and the cylinder, and a relatively reduced passage through the cylinder wall between said fitting and the interior of the cylinder.

10 In testimony whereof I affix my signature.
CHARLES R. MINER.
